UNITED STATES PATENT OFFICE.

PAUL P. RUHE, OF HOBOKEN, NEW JERSEY, AND WILLIAM A. SONEN, OF NEW YORK, N. Y.

SEWING MACHINE.

1,405,443.

Specification of Letters Patent. Patented Feb. 7, 1922.

Application filed December 31, 1920. Serial No. 434,280.

To all whom it may concern:

Be it known that we, PAUL P. RUHE and WILLIAM A. SONEN, both citizens of the United States, and residents, respectively, 5 of Hoboken, in the county of Hudson and State of New Jersey, and Bronx, New York, have invented certain new and useful Improvements in Sewing Machines, of which the following is a specification.

10 This invention relates to sewing machines of the type known as overseaming machines, such as are commonly used in sewing furs and the like.

One of the objects of the invention is to 15 improve the mechanism for operating the looper. Another object is to provide a looper mechanism which can be operated at a high rate of speed with a very small amount of wear. Another object is to provide 20 means for quickly making adjustments to compensate for wear on the various parts of the looper mechanism. Another object is to provide mechanism for securing the necessary movements of the looper without resorting to the use of slots for guiding the 25 looper in its movements.

A further object is to provide an improved mechanism for intermittently feeding the work being sewed. A still further 30 object is to combine and co-ordinate the various instrumentalities herein described so as to effectively perform the functions set forth. Other objects will be apparent from the following description when read in connection with the accompanying drawings in 35 which—

Fig. 1 is a plan view of a machine embodying our invention, the top plate being sectioned off in the interest of clearness;

40 Fig. 2 is a longitudinal section on the staggered line 2—2 of Fig. 1;

Fig. 3 is a transverse section on the line 3—3 of Fig. 1;

Fig. 4 is a skeleton view substantially on 45 line 4—4 of Fig. 3 showing the looper actuating mechanism;

Fig. 5 is a detail view showing the mechanism for actuating the feed wheels intermittently;

50 Figs. 6 and 7 are diagrammatic views showing two different positions of the looper and needle in the act of forming a stitch.

Referring to the drawings, the main drive shaft 1 is mounted in suitable bearings 2 and 3 in the frame 4 of the machine. This

shaft is driven by a pulley 5 connected by means of a belt, not shown, to any suitable source of power. An eccentric 6 secured to the main drive shaft operates between the downwardly extending arms 7 and 8 of a 60 yoke 9 carried by the needle bar 10. The lower end of the arm 8 is notched out at 11 for co-action with a fixed guide pin 12. The needle bar is guided in the usual manner through openings 13 and 14 formed in 65 the end walls 15 and 16 of the supporting frame. A suitable head 17 is clamped or otherwise secured to the forward end of the needle bar 10 and carries a needle 18.

For operating the looper we employ two 70 eccentrics, one adapted to produce the reciprocatory movement necessary to carry the loop of thread from one side of the work to the other side, and the other adapted to move the looper vertically toward and away 75 from the needle. We also provide a floating support in which the looper is pivotally mounted so that it can be swung laterally across the path of travel of the needle.

The floating support for the looper 80 comprises an intermediate yoke-shaped member 19 having downwardly extending arms 20 and 21 between which an eccentric 22, secured to the shaft 1, operates to move the looper back and forth in substantially the 85 same direction of travel as the needle. Secured to the forward part of the intermediate member 19 is a tubular guide 23 and to the rear portion of the intermediate member is a similar tubular guide 24. The 90 looper 25 is pivotally mounted in the members 23 and 24, collars 26 and 27 secured thereto prevent its longitudinal movement relatively to the floating support, but permit it to turn axially therein. The looper 95 is provided with the usual curved end 28 having a hook 29 formed on the end thereof for engagement with the thread.

Lateral extensions 30 are formed on the tubular member 23 and engaged by pivot 100 screws 31 secured in the outer ends of a yoke-like link 32 forming one-half of a toggle 33, the other half of which is formed by links 34 secured to a shaft 35 carrying a downwardly extending lever 36 which is 105 adapted to be rocked by an eccentric strap 37 actuated by an eccentric 38 secured to the main shaft 1. The rear end of the floating support is secured to a fitting 39 by a set screw 39^a, said fitting is carried on pivot 110

screws 40 adjustably mounted in links 41 and provided with suitable jam nuts to lock them in place. The links 41 are carried by a shaft 42 journalled on pivot screws 43 secured in the main frame of the machine. These pivot screws also have the jam nuts to lock them in their adjusted positions.

As thus constructed it is apparent that as the eccentric 22 revolves the intermediate 10 member 19 will be moved back and forth and carry the looper with it. During this movement the rear end of the floating frame which is supported on the links 41 will move in a true arcuate path and will be raised 15 and lowered a slight distance as the link passes to and from the vertical dead center. It is necessary to give the looper a greater vertical movement than that obtainable by such a simple link. And this greater movement 20 is obtained by utilizing the toggle 33, above described, which is actuated by the eccentric 38. As this eccentric rotates it straightens out the toggle to raise the looper and then breaks the toggle to again lower 25 said looper to bring its hooked end 29 low enough to engage the looped thread adjacent to the end of the needle.

Heretofore such a raising and lowering movement has been secured by utilizing a 30 cam slot with a roller carried by the looper frame, and in practice this has been found decided objectionable due to the excessive wear and noisy operation. As the shaft rotates and the toggle 33 is straightened out 35 the whole floating frame pivots about the screws 40 and raises the hooked end of the looper 29 to the maximum height required and this vertical stroke can be readily varied by adjusting the member 24 longitudinally in the fitting 39 and securing it by means of the set screw 39^a. When the parts 40 become worn in use it is a simple matter to take up such wear by adjusting the pivot screws 31, 30, 43, etc.

45 For swinging the hooked end 29 of the looper laterally across the path of travel of the needle, we employ a crowned cam roller 44 carried on an arm 45 secured to the looper 25 adjacent to the rear arm 21 of the 50 intermediate supporting member. This roller runs in a cam groove 46 formed in a cam 47 carried by the main drive shaft 1.

The operation of the parts thus far described is as follows. Starting with the needle 55 in its rearward position as shown in Figs. 2 and 4, as the shaft 1 rotates clockwise the eccentric 6 will advance the needle and the looper hook 28 will first move upwardly a short distance drawing the loop with it and then will be moved downwardly by the action of the eccentric 38 and toggle 33 so as to bring the loop to the position 60 shown in Fig. 6 in which the needle is about to pass through the loop. The needle will 65 continue forward through the loop and the

work and the looper will swing transversely by action of the cam roller 44 and will then be raised and advanced approximately to the position shown in Fig. 7 at which time the needle is being retracted to form another 70 loop. The looper is now swung transversely by action of the cam 47 carrying the loop to one side, and the looper is then retracted by eccentric 22 to the position shown in Fig. 4 ready for another cycle of operations as 75 above described.

After the needle has been retracted the work is fed along by the feed wheels 48 and 49, the former being freely mounted on a bracket 50 and the latter being secured to a 80 shaft 51 carrying a worm gear 52 which meshes with a feed worm 53 loosely mounted on a short shaft 54 which is fixed in a bracket 55 carried by the main frame of the machine. A disc 56 is secured to the worm 53 and adapted to drive it intermittently. This disc has a peripheral flange 57 which is engaged by the notched end 58 of a friction shoe 59. The inner end 60 of this shoe contacts with a shoulder 61 formed on a lever 62 which is oscillated by a rocking arm 63 mounted loosely on an adjustable stud 64 secured to the frame of the machine by a wing nut 65. The rocking arm is provided with a slot 66 to permit slight longitudinal play relatively to the stud 64. An eccentric strap 67 actuated by an eccentric 68 carried on the main shaft 1 serves to rock the arm 63.

Fixed on the shaft 54 is a clutch member 69 having inclined surfaces 70. The disc 57 is provided with an annular groove 71 and clutch balls 72 are pressed by springs 73 into engagement with the inclined walls 70 and said groove to prevent the backward rotation of the disc 57.

When the eccentric 68 lifts the strap 67 it will rock the arm 63 about the stud 64 and also move it longitudinally a short distance and impart a downward rocking movement to the lever 62. This will raise the shoulder 61 and cause the shoe 59 to grip the flange 57 and move the disc in the direction of the arrow α shown in Fig. 5, the clutch balls at this time slipping along the inclined faces of the fixed member 69. When the eccentric makes its downward stroke and rocks the arm 63 in the opposite direction, the lever 62 will be moved upwardly and a spring 74, secured at one end to the shoe, and on the other end to a pin 75 carried by the lever 62, will cause the shoe to be pulled back freely on the flange 57, the balls 72 at this time preventing the movement of the disc. The stud 64 passes through a slot 64^a in the main frame of the machine and by adjusting this stud laterally it is clear that the effective stroke of the arm 63 can be varied to enable the operator to adjust the feed of the work.

Though we have described with great par- 130

ticularity of detail the embodiment of our invention illustrated, yet it is not to be understood therefrom that the invention is restricted to the particular embodiment disclosed. Various modifications thereof in detail and in arrangement of parts and the substitution of mechanical equivalents may be made by those skilled in the art without departing from the invention as defined in the following claims.

What we claim is:

1. An overseaming sewing machine including a reciprocating needle, a looper and a floating support comprising front and rear end members for pivotally carrying said looper and an intermediate yoke secured to said end members, means co-acting with said yoke to reciprocate the floating support, links arranged to move in an arcuate path pivotally secured to one of said end members, toggle links operatively engaging the other of said end members, and means for

moving said toggle links to move the looper toward and away from the needle.

2. An overseaming sewing machine including a reciprocating needle, a looper and a floating support comprising front and rear end members for pivotally carrying said looper and an intermediate yoke secured to said end members, means co-acting with said yoke to reciprocate the floating support, links arranged to move in an arcuate path pivotally secured to one of said end members, toggle links operatively engaging the other of said end members and means for moving said toggle links to move the looper toward and away from the needle and means for rocking said looper to swing it across the path of travel of the needle.

In witness whereof, we have hereunto signed our names.

PAUL P. RUHE.
WILLIAM A. SONEN.
